[57] CLAIM

The ornamental design for a pump sprayer pressure
tank or similar article, as shown and described.

DESCRIPTION

FIG. 1 is a perspective view of a pump sprayer pressure
tank showing my new design;

FIG. 2 is a front elevational view thereof, the rear being
substantially similar in appearance;

FIG. 3 is a left side elevational view thereof, the right
side being substantially similar in appearance;

FIG. 4 is a top plan view thereof;

FIG. 5 is a bottom plan view thereof; and

FIG. 6 is a right side elevational of a second embodiment
thereof, the only difference residing in the height
of the tank.

FIG.1

FIG.4

FIG.5

FIG.2

FIG.3

FIG. 6
